Egon Sjöström ATTORNEY

UNITED STATES PATENT OFFICE

MORRIS STAW, OF NEW BRUNSWICK, NEW JERSEY

GARMENT

Application filed November 3, 1931. Serial No. 572,759.

This invention relates to garments and is particularly directed to a garment which may either be worn as a coat or as a shirt, and when worn as a coat has the appearance 5 of both a coat and shirt.

An object of this invention is to provide a garment of the character described which may be easily made of light shirting material without any support of canvas lining or 10 padding ordinarily used in men's coats, and yet have the usual appearance of a man's coat and be worn as such, particularly in warm weather.

A further object of this invention is to 15 provide a garment of the character described having a detachable front portion simulating a shirt front and a collar simulating portion; and improved means for attaching the front to the remainder of the garment, the 20 construction of the garment including means for receiving a tie passed around a garment collar and tied at the front, whereby the garment has the appearance of a combined coat and shirt.

A further object of this invention is to 25 provide a neat and attractive garment of the character described which shall be relatively inexpensive to manufacture, comprise few and simple parts, which shall be easy to don and doff and which shall yet be practical and efficient to a high degree.

Other objects of this invention will in part 30 be obvious and in part hereinafter pointed out.

The invention accordingly consists in the 35 features of construction, combinations of elements, and arrangement of parts which will be exemplified in the construction hereinafter described, and of which the scope of application will be indicated in the following claims.

In the accompanying drawing, in which is 40 shown one of the various possible embodiments of this invention.

Fig. 1 is a front view of the garment on a 45 figure worn as a shirt;

Fig. 2 is a front elevational view of the 50 garment when worn as a coat;

Fig. 3 is a rear perspective view of the 55 structure shown in Fig. 1;

Fig. 4 is a rear elevational view of the structure shown in Fig. 2;

Fig. 5 is a view showing the portions of 55 the garment which are sewed together to produce the garment;

Fig. 6 is a front elevational view of the detachable garment front;

Fig. 7 is a view similar to Fig. 6 but illustrating a modified construction; and

Fig. 8 is a front view of a collar point 60 used in the front shown in Fig. 7.

Referring now in detail to the drawing, 10 designates a garment embodying the invention here shown for the purpose of illustration as a garment which may be worn either as a shirt or as a coat. The garment is particularly useful for summer wear and may be made of ordinary shirting material and without canvas lining or backing. As 15 will appear hereinafter, the garment is simply made and the design thereof is such that it may readily be made of light shirting material and yet have the appearance of a man's coat. As will appear hereinafter, when the garment is worn as a coat, it has the appearance 20 of both a coat and shirt.

The garment 10 is provided with a back 25 section or portion 11 made of a top piece 12, a bottom piece 13 and an intermediate piece 14 stitched to the piece 12 as at 15 and stitched to the piece 13 as at 16. The section 14 may be formed with a pair of box pleats 18 of the usual construction. A belt simulating member 20 may be sewed to the back as at 21 and 30 22 for covering the line of stitching 16 and the bottom ends of the box pleats 18. The back section 11 is provided with a curved edge 23 for the back of the neck and edges 24 forming portions of the arm holes.

Stitched to the side edges 26 and 27 of the 35 back portion 11 are a pair of symmetrical side or front sections 30, one only of which is shown in Fig. 5. The sections 30 obviously 40 are disposed over the front of the body and are attached together by means of complementary buttons 31 and button holes 32, so that the garment may be doffed in the manner 45 of a coat and need not be pulled off over the head. It will be noted that the sections 30 50 are provided with edge portions 33 which are 55 100

stitched to the edge portions 26 and 27. The stitching, however, extends only to the point 34 above the bottom edge, leaving a slit or unattached portion 35 to provide the garment with tails to simulate shirt tails which may be gathered and tucked into the trousers when the garment is worn as a shirt. The sections 30 are formed with curved edge portions 36 cooperating with the edge portions 10 24 and forming portions of the arm holes. The edge portions 37 of the section 30 are stitched to the edge portions 38 of the section 11 to form the shoulder seams of the garment. The section 30 may furthermore 15 be formed with a curved edge 39 and a lapel portion 40 which may be folded rearwardly about the line 41 to the dotted line position thereof, as shown in Fig. 5. Attached to the curved edge portion 39 is a member 42 formed 20 of two similar symmetrical portions 43 stitched together as at 44. The member 42 is obviously stitched at the edges 42a thereof to both sections 30, and is also stitched at the edge 43a thereof to the edge portion 23 of 25 the back section 11, and thus forms the collar for the garment. The member 42 is folded along the line 45 which is continuous with the folded lines 41 about which the lapels 40 are folded.

30 Pockets 46 and 47 of usual construction may be sewed to one or both of the sections 30. For the purpose hereinafter stated, each section 30 is provided with a pair of spaced buttons 48, 49 sewed to the inside thereof at 35 points thereon spaced inwardly from the folded edge 41. Sewed over the lapel portions 40 of the sections 30, and over the collar member 42 is a member 50 folded along the line 51 which coincides with said folded lines 41 and 45. The member 50 forms the part of 40 the lapel and collar which shows when the garment is worn.

Each sleeve 53 is formed from the blanks 54 and 55, shown in Fig. 5 which are stitched 45 together along the line 57. The blank 54 is formed with an edge portion 58 stitched to the edge portion 59 of section 55. The outer edge portion 60 of section 54 is stitched to the edge 61 of the section 55. The curved 50 edges 62 and 63 are sewed to the edge portions 36 and 24 which form the arm holes for the garment.

To provide a front for the garment whereby when the garment is worn as a coat, it 55 has the appearance of both a coat and shirt worn beneath said coat, there is provided a member 70 shown in Fig. 6. Said member 70 may be formed of one piece or of sections 71 and 72 provided with complementary but- 60 ton holes and buttons 73 for attaching the two members together. The portions 71 and 72 are cut out, as at 74 and 75 to fit the neck of the wearer. One of the sections 72 may be provided with an extending strip 76 to pull 65 the shirt front down. Each of the sections

71 and 72 are formed with a pair of spaced button holes 77 and 78 adjacent the outer side edge thereof for receiving the buttons 48 and 49 sewed to the inside of the garment sections 30. Thus the front member 70 may be attached to the sides of the garment to simulate a shirt front.

Each section 30 is further provided with a slit or opening 79 adjacent curved edge 39 thereof for receiving a tie 80. Thus the tie 75 80 may be passed around the rear of the collar portion of the garment and then passed inwardly into the interior of the garment through the openings or slits 79. The tie 80 ends may then be tied at the front to overlie the curved cut out edges 74 and 75 of the member 70, as illustrated in Fig. 1.

There is shown in Fig. 7 a shirt front simulating member 70a illustrating a modified construction. The member 70a may likewise be formed of sections 71a and 72a attached together by means of buttons and button holes or in the like manner. Attached to the edge portions 74a and 75a of the sections 71 and 72 are collar points 81 having strips 82 folded over said edge portions and stitched thereto. The points 81 simulate the front of a shirt collar and the tie may be passed beneath said points and tied into the usual tie knot. As shown in Fig. 2, the garment simulates a coat and shirt worn thereunder. As illustrated in Figs. 1 and 3, however, the garment may be tucked within the trousers for simulating a shirt. The entire garment may be made of light shirting material such as silk or cotton and may be readily cut to accurately fit the wearer. The box pleats and belt portion at the back of the garment gives the same the appearance of either a shirt or a coat, depending upon the way the garment is worn.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing, is to be interpreted as 110 illustrative and not in a limiting sense.

Having thus described my invention, I claim as new and desire to secure by Letters Patent:

1. A garment having a rear section and a pair of front sections stitched to said rear section and buttoned together at the front, and a shirt front simulating member attached to said front sections, said front sections having openings therein on opposite sides of the collar to permit a tie to be passed between the collar and other portions of the garment into the interior of the garment and through said openings whereby the tie ends may be tied at the front of the garment.

2. A garment comprising a coat having sleeves and adapted to be buttoned together at the front and having a collar and lapels and a shirt front simulating member attached 5 to the garment adjacent the lapels and having collar portions, and openings on opposite sides of the neck of said coat adjacent the collar portion thereof to permit a tie to be passed beneath the coat collar through said openings 10 and beneath the collar portions of said shirt simulating member whereby the tie ends may be tied at the front of said member.

3. A garment comprising a coat made of shirting material and buttoned at the front 15 and provided with sleeves, said garment having slits in the sides thereof and adjacent the lower edge thereof to permit the lower portion of the garment to be tucked within the trousers whereby the garment may be worn 20 as a shirt, said garment having a V-shaped neck portion, and a shirt front simulating member removably attached to said garment at said neck portion and being provided with permanent collar point portions for receiving 25 a tie therebeneath, the back portion of said garment comprising an upper section, a lower section and an intermediate section stitched to said upper and lower sections, said intermediate section being formed with a pair 30 of spaced box pleats extending from the upper to the lower edge thereof and a belt simulating member stitched to said intermediate section and lower section and covering the line of stitching interconnecting said intermediate section with said lower section. 35

4. A garment comprising a coat made of shirting material and buttoned at the front and provided with sleeves, said coat having slits in the sides thereof and adjacent the 40 lower edge thereof to permit the lower portion of the coat to be tucked within the trousers whereby the coat may be worn as a shirt, said coat having a V-shaped neck portion and a shirt simulating member attached to the 45 inside of the coat, at said neck portion, said coat being provided with a pair of openings on opposite sides of the neck portion whereby a tie may be passed around the rear of the coat and the tie ends passed inwardly through 50 said openings so that the tie ends may be tied at the front of the garment adjacent the upper edge of the shirt front simulating member.

5. A garment comprising a coat portion 55 split entirely down the middle at the front of the garment and having a collar and lapels, said garment being split at the sides adjacent the bottom ends thereof to permit the lower portion of the coat to be tucked within 60 the trousers of the wearer in the manner of a shirt, and a shirt front simulating member removably attached to the inside of the garment, said member being provided with permanent folded over collar portions for receiving 65 the tie therebeneath.

6. A garment adapted to be worn on the upper portion of the body of the wearer, having a body portion provided with sleeves, a collar and lapels, and being split entirely down the front, and extending below the 70 waist of the wearer whereby the garment may be worn and doffed in the manner of a coat, a shirt front simulating member removably attached to the garment to permit the same to be worn as a combination coat and shirt, the portions of the coat extending below the 75 waist of the wearer being adapted to be tucked within the trousers of the wearer, and said garment being made entirely of relatively light shirting material to permit the 80 garment to be worn as a shirt.

In testimony whereof I affix my signature.
MORRIS STAW.
